UNITED STATES PATENT OFFICE.

STEVEN ELMER GUTRIDGE, OF NEWARK, OHIO.

BALING-PRESS.

No. 851,131.

Specification of Letters Patent.

Patented April 23, 1907.

Application filed August 8, 1906. Serial No. 329,794.

To all whom it may concern:

Be it known that I, STEVEN ELMER GUTRIDGE, a citizen of the United States, residing at Newark, in the county of Licking and State of Ohio, have invented a new and useful Baling-Press, of which the following is a specification.

This invention relates to baling presses, and has for its principal object to provide a press of simple and compact construction in which the power employed in forcing the plunger during the compression movement may be gradually increased in order to compensate for the gradual increase in the resistance of the hay as the latter becomes more and more compact.

A further object of the invention is to provide a novel form of plunger operating mechanism in which toggle levers are used to force the plunger forward, and in which the toggle operating mechanism is so arranged as to gradually increase the force exerted during the compression movement of the plunger.

25 A still further object of the invention is to provide a plunger operating mechanism including a toggle lever, and means for automatically shifting the point at which power is applied to the toggle lever, so that increased leverage may be obtained during the compression movement.

30 A still further object of the invention is to provide a novel form of power head and mechanism for transmitting movement therefrom to the plunger, all of the mechanism being arranged with a view of gradually increasing the leverage force exerted toward the end of the compression movement.

35 A still further object of the invention is to provide a novel form of folder for co-operation with the plunger in feeding the hay from the hopper section into the baling chamber proper.

40 A still further object of the invention is to provide a hay folder or feeder that is yieldably mounted to permit the passage of the plunger, and further to so arrange the feeder that the weight of the operator or man in control of the feeding may be utilized in holding the feeder down in proper position.

45 A still further object of the invention is to provide a novel form of tension mechanism for adjusting the cross sectional area of the baling chamber in order to retard the movement of the bale.

A still further object of the invention is to provide a novel form of plunger and plunger returning mechanism.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a side elevation, partly in section, of a baling press constructed in accordance with the invention. Fig. 2 is a plan view of the same. Fig. 3 is a transverse sectional view of the press looking in the direction of the hopper, on the line 3—3 of Fig. 1. Fig. 4 is a transverse section through the press box on the line 4—4 of Fig. 1. Fig. 5 is a detail perspective view of the folder or cutter bar, detached. Fig. 6 is a transverse sectional view through a portion of the machine at the power head end of the machine. Fig. 7 is a sectional plan view of a portion of the power head end of the machine. Fig. 8 is a transverse sectional view drawn to an enlarged scale, illustrating the guide for the thrust bar and the chain guiding rollers. Fig. 9 is a detail view of the whipping mechanism.

90 Similar numerals of reference are employed to indicate corresponding parts throughout the several figures of the drawings.

The baling press shown in the drawing is of the portable type, its main sill 10 being mounted on wheeled axles 11, the forward axle being preferably provided with a king pin connection in order to permit the proper guiding of the machine toward and from the field of operation. The main sill 10 is preferably formed of two sections, united by suitable bolts 12, and the sill structure is strengthened by a pair of truss bars 13 the intermediate portions of which bear under transversely disposed blocks 14 carried by the sill. The truss bars are preferably formed of sections having right and left hand screw threads which are connected by turn buckles 15 to permit of the necessary adjustment. The baling chamber 16 is located at one end of the sill, the sill being used as the bottom of the baling chamber, and the sides being

formed of spaced slats 17 which are supported by suitable uprights 18.

Pivoted on pins 19 carried by one of the uprights is a tension board 20 which forms the top of the baling chamber and which may be thrust down by means of a cross bar 21 in order to exercise more or less resistance to the passage of the bale. This bar 21 is provided with openings for the passage of cranked rods 23 having operating handles 24 and provided with rigid collars 25 which bear against the upper face of the bar 21. The lower ends of the rods 23 pass through openings in a cross bar 26 below the main sill 10 and enter stationary metallic nuts 27, and as the lower ends of said rods are threaded, the turning of the handles will either increase or decrease the cross sectional area of the baling chamber and exercise more or less resistance to the passage of the bale.

At the entrance end of the baling chamber is a hopper 29 having convergent walls of the usual type, and the hay or other material fed into the hopper is acted upon by the plunger head 30 and forced into the baling chamber proper, the successive charges of material being retained in place by spring fingers 31 that are secured to the sides of the baling chamber and project inward therefrom, these fingers engaging and holding the charges of hay or other material that are forced into the chamber by the action of the plunger.

In order to insure the introduction of the full charge of the hopper section into the baling chamber and to prevent the passage of any of the material over the top of the tension board 20, said board carries a folder or feeder 34. This folder or feeder is in the form of a bar having a curved lower face and of a length equal to the width of the hopper chamber. To the opposite ends of the feeder or folder are secured straps 35, preferably formed of spring metal, and these spring metal straps are secured to the tension board. Normally the curved lower edge of the folder 34 is in a horizontal plane below the top of the plunger 30, and as the latter moved forward, the hay or other material will be crowded down under the folder and then as the plunger come forward the folder will be raised slightly, so that all of the material will enter under the tension board. In order to increase the downward pressure on the folder 34, the spring strips 35 carry a foot board 37 on which the operator in charge of the feeding may stand.

The plunger is carried by a plunger rod 40 that is held in a central position by a number of guides 41 engaging its opposite sides, its upper and lower faces, and near the outer end of the plunger is secured a bracket 42 carrying a roller 43 arranged to run on the sill 10 for the purpose of supporting said plunger rod.

65 The plunger receives movement during the

compression operation through mechanism hereinafter described, and after each of these movements is turned to its initial position by a weight 45. This weight is preferably in the form of a bucket like member arranged to contain loose blocks or weights of any kind, so that the load may be increased or diminished as required. The weight is attached to one end of a cord or chain 46 which passes over guiding sheaves 47, 48 and 49 and is attached at its opposite end to the plunger. The sheave 47 is carried by a diagonally arranged bar 50 which is secured across the outer end of the hopper section and serves, also, as a strengthening brace for the hopper.

At the power head end of the machine is secured a plank 50' which, in connection with the sill 10, serves to support a pair of transverse sills 51, and these transverse sills serve as supports for a pair of cross bars 52 which are arranged to form an upper journal bearing for the revoluble shaft 53 of the power head 54. The lower end of the shaft 53 is preferably tapered and is stepped in a bearing 55 that is carried by the sill 10, and plank 50', the bearing being preferably made in two parts to permit such adjustment as may be necessary to compensate for wear. That sill 51 nearest the baling chamber is provided with a recess for the passage of a thrust bar 57, and the sill is strengthened by a metallic brace 58, as shown in Fig. 6.

The power head includes a pair of diametrically opposed arms 60 which are provided at their outer ends with anti-friction rollers 61 that are adapted to successively engage with the adjacent end of the thrust bar 57, and this end of the thrust bar is preferably provided with a strengthening or reinforcing cap 62 which may be renewed when worn. Secured to the cap is a pin 63 which extends through an arcuate slot 64 that is struck from the axis of the shaft 53. This slot extends through a plank 65 that is secured to the bracing strap 58, of each of the transverse sills, and preferably is supported a slight distance above the main sill 10. The pin and groove serve to maintain the heel end of the thrust bar in proper position with respect to the anti-friction rollers of the power head, and the latter will successively engage with said thrust bar and carry the same from one end of the slot to the other, the thrust bar being restored to its initial position after each operation by the weight 45 through the connections hereinafter described.

To the top of the shaft 53 at a point above the cross bars 52 is secured a two arm lever 67. To one arm of this lever is secured a sweep 68, the outer end of the sweep being connected to the opposite arm of the lever by a tension rod 69'. The outer end of the rod 69 passes through an opening formed in the sweep and is provided with an eye 70 to which the draft animal may be attached, and

the opposite end of said rod passes through an eye formed in the lug 71 and carries a nut 72 by which the rod may be adjusted in order to properly brace the sweep.

Secured to the sill 10 at a point adjacent to one of the transverse sills is a transversely disposed bar 75, the ends of which extend a considerable distance beyond the sides of the sill and are braced by bars 76. To the bar 75 is pivoted a pair of levers 77, the outer ends of which are pivoted to levers 78, and these in turn are pivoted to lugs projecting from the bracket 42 of the plunger rod, the mechanism constituting a double toggle lever through which movement is imparted to the plunger rod during the compression stroke.

Secured to the sill 10 is a pair of spaced bars 80 which are connected by slightly rounded vertical bars 81, the space between these bars forming a guide for the outer end of the thrust bar. The bars 80 carry pins 84 on which are mounted sheaves 85, and these sheaves serve as guides for chains 86. One end of each chain is extended to a point adjacent to the end of the thrust bar, and is connected to an equalizing bar 87 that is pivoted on a pin 88 carried by said thrust bar, the equalizing bar swinging freely on its pivot in order that equal force may be transmitted to each of the levers without regard to the varying angular position of the thrust bar.

The two levers 77 of the toggles are surrounded by yokes 90, and each yoke carries an anti-friction roller 91 that bears against the rear side of the lever. The forward end of each yoke is connected to a chain 86, and during the operation of the thrust rod, movement will be transmitted through the chains 40 to these yokes, and from thence to the levers 77 of the toggle, the yokes travelling along the length of the levers during the operation as the angular position of the lever to the line of the pull of the chain varies, and there is thus 45 an automatic adjusting of the point of application of the power to the toggles during the compression movement of the plunger.

During the compression movement of the plunger, the turning of the power head from the sweep will bring the anti-friction roller 61 of the two armed lever 60 into engagement with the heel end of the thrust bar, and the latter will be moved in the direction of the baling chamber. During the beginning of 55 this movement, the yokes 90 will be some distance from the point of connection of the toggle levers 77 and 78, but as the operation continues, the yokes will automatically move nearer and nearer to this point of connection 60 as the line of pull of the chain and the angles of the levers 77 vary, so that the pull will be exerted at a point which constantly increases in distance from the fixed pivots of the lever 77, thus increasing the leverage force and the 65 power which is exerted upon the toggle levers.

ver, and this increase in force takes place principally during the latter part of the compression movement when the resistance of the hay is increased. At the same time as the angular relation of the operating arm of 70 the power head and the thrust bar grows more obtuse, the power exerted will be materially increased toward the latter end of the stroke. After each roller 61 leaves the heel end of the thrust bar, the plunger is drawn 75 back to its initial position by the weight 45, and the movement of the plunger head is transmitted through the plunger rod and the toggle levers to the chains, and from hence to the thrust bar, so that the latter, also, is 80 restored to initial position in readiness to be engaged by the next roller of the power head.

The sweep is provided with an opening for the passage of a pin 95 which carries a sheave 96, and a whip socket 97, the latter being 85 preferably in the form of a suitable clamp for holding the whip x. Around the sheave extends a cord or cable 99 which is connected at one end to an eye 100 on the sweep by means of a helical tension spring 101. The cord is 90 guided around a sheave 102 near the power head end of the sweep, and thence passes through an eye in a bracket 103 and runs between a pair of guiding rollers 105 that are carried by a standard 106 to the hopper. 95 The whip is thus placed under the control of the attendant stationed at the hopper and may be used as required. It will be noted by reversing the direction in which the cord is coiled on the sheave 96 the whip may be 100 caused to operate either on the right or the left.

I claim:—

1. In a baling press, a baling chamber, a compression plunger, a plunger rod, a toggle mechanism connected to the plunger rod, a slidably mounted yoke embracing one of the toggle levers, and movable automatically along the length of the lever, a thrust bar, a power head for actuating the same, and a 105 flexible connection between the thrust bar and the yoke.

2. In a baling press, a baling chamber, a compression plunger, a plunger rod, a toggle mechanism through which movement is imparted to the plunger rod, a thrust bar, a power head for actuating the same, a yoke slidably mounted on one of the toggle levers, a flexible connection between the thrust bar and the yoke, and a guiding means for said 115 120 flexible connection.

3. The combination with a baling chamber, of a compression plunger, a plunger rod connected thereto, a pair of oppositely disposed toggles, each connected at one end to a 125 fixed point, and at the opposite end to the plunger rod, a slidably yoke on one lever of each toggle, a thrust bar, a power head for actuating the same, an equalizing bar pivoted to the thrust bar, flexible connections 130

extending between the equalizing bar and the yokes, and guiding means for said flexible connections.

4. In a baling press, the combination with 5 a baling chamber, of a compression plunger, a plunger rod, a pair of toggles, each having one end connected to a fixed point and the opposite end to the plunger rod, slideable yokes mounted one on each toggle, a thrust 10 bar, a power head for moving the same, an equalizing bar pivoted to the thrust bar, chains extending from the equalizing bar to the yokes, a guiding frame for the outer portion of the thrust bar, and chain guiding 15 sheaves carried by said frame.

5. In a baling press, a baling chamber, a compression plunger, a plunger rod a toggle mechanism connected to the plunger rod, a thrust bar, means for connecting the thrust 20 bar to the toggle mechanism, a revoluble power head including a pair of arms arranged to successively engage the heel of the thrust bar, a frame member having an arcuate slot struck from the center of rotation of the 25 power head, and a guiding pin carried by the heel portion of the thrust bar and extending into said slot.

6. In a baling press, a longitudinal sill, truss rods for strengthening the sill, a baling 30 chamber arranged at one end of the sill and of which the sill forms the body, a power

head supported at the opposite end of the sill, transversely disposed sills carried by the main sill, an upper bar carried by the transverse sills and forming an upper bearing for 35 the power head, a transversely disposed bar secured to the main sill, toggle levers pivoted to said bar and to the plunger rod, a thrust bar receiving motion from the power head, a thrust bar actuating frame secured to the 40 main sill, and equalizing bar pivoted to the thrust bar, slideable yokes embracing portions of the toggles, flexible connections between the yokes and the equalizing bar, and guiding 45 sheaves for said flexible connection, said sheaves being supported by the thrust bar guiding frame.

7. In a baling press, a baling chamber, a hopper, a compression plunger, a curved plate forming the top of the baling chamber, 50 a pair of spring strips secured at one end to the plate, a folding bar carried by said strips and arranged slightly in advance of the compression chamber, and an operator's foot-board resting on said spring strips.

In testimony that I claim the foregoing as my own, I have hereto affixed my signature in the presence of two witnesses:

STEVEN ELMER GUTRIDGE.
